UNITED STATES PATENT OFFICE.

JEFFERSON CLARK GIBSON, OF CHICAGO, ILLINOIS.

HYDROCARBON-BURNER.

1,318,549.

Specification of Letters Patent.

Patented Oct. 14, 1919.

Application filed August 30, 1918. Serial No. 252,057.

To all whom it may concern:

Be it known that I, JEFFERSON CLARK GIBSON, a citizen of the United States of America, and a resident of Chicago, county 5 of Cook, and State of Illinois, have invented certain new and useful Improvements in Hydrocarbon-Burners, of which the following is a specification.

This invention relates to hydrocarbon 10 burners, mainly those designed for use in the fire boxes of stoves and furnaces, and the main objects of the invention are to provide an improved form of burner including certain appurtenances of novel construction adapted to insure efficient operation and to more readily facilitate proper cleaning and care of the device; to provide a vaporizer wick of improved and more durable form adapted to better facilitate its 15 interchange, reversal and removal from the vaporizing chamber or tube; to provide a carbon removing and cleaning attachment of improved form connected permanently in working contact with the burner or vapor 20 jet aperture and connected for ready manual actuation from a distance; to provide an improved form of mounting for the torch cup; to provide a guide member and mixing chamber of improved form adapted 25 to cause efficient distribution and combustion of the fuel mixture; to provide an improved form of baffle plate or button in said mixing chamber; and to provide an improved form of closure for the end of the 30 burner pipe.

An illustrative embodiment of the invention is shown in the accompanying drawings, in which—

Figure 1 is mainly a side elevation of the 40 burner and includes an edgewise view of the supporting plate to which it is clamped.

Fig. 2 is a section at 2—2 on Fig. 1.

Fig. 3 is a side view of the wick member with part of the wick proper broken away.

In the embodiment shown in the drawings, the burner comprises a U-shaped tube 1 disposed with its arms 2 and 3 in a horizontal position the one over the other, the lower arm 3 being closed, as by the threaded 45 cap 3', and provided with a jet aperture 4 in its upper side, and also having the starting cup 5 and jet cleaner 6 mounted thereon.

The upper or fuel supply arm 2 extends forward beyond the tip of the lower arm, 50 and the outer tip of said upper arm is threaded and provided with rigid mount-

ing means in the form of a pair of nuts 7 arranged for clamping the adjacent wall member 8 of the stove or other inclosing device between them for supporting the 60 burner.

A sheet metal shield or flame distributor 9 is disposed on the upper side of and is secured rigidly to said upper arm 2 directly over and coaxial with the jet aperture 4. 65 Said plate has numerous small perforations 10 evenly spaced apart throughout its body and serves to spread the flame and heat and to distribute same uniformly over a large area in a most efficient manner and 70 in a form corresponding to the shape of the plate which is preferably circular. The edges of the plate are to advantage curved downward somewhat as at 11. Said plate is clamped to the arm 2 by a pair of U- 75 bolts 12, as shown clearly in the drawing.

The upper arm 2 is provided also with a wick 13 of heat resistant material, preferably asbestos. Said wick is of fabricated or woven tubular character and by itself 80 alone is flexible, but it has a rigid metal stiffening core 14, inclosed thereby, extending substantially throughout its length. Said core assists in distributing the heat and also enables more ready handling especially when inserting the wick into its vaporizer housing 2. Each end of the wick is closed and is formed and adapted to be engaged by a wick removing implement 15. For this purpose a wire is threaded through 85 the tip of the wick and wick rod, which is perforated, therefor, and looped in such manner as to provide a closed link 16. A manual instrument, such as a button-hook or the like, may serve as the implement 15 90 for engaging the ring or loop 16 to withdraw the wick and inclosed rod from the arm 2.

The jet orifice cleaner 6 comprises a curved wire 18 which extends loosely into 100 the jet aperture 4 and is supported by an agitator lever 20 fulcrumed on the lower arm 3 near said aperture. Said lever 20 is shown in the form of a sheet metal strap bent at one end to form a loop 20' which 105 is mounted rockably for limited universal movement on arm 3, and having its other end extended laterally as at 20" for engagement with a rod 21 which extends forward through the stove front 8 for manual 110 operation by the attendant.

The lever 20 and the starting cup 5 are

preferably attached to said lower arm by the same means, namely, a ring 23 surrounding said arm, and a pair of screws 25 and 26 disposed preferably at approximately 5 90° to each other, the one projecting downward and supporting the cup 5, and the other being disposed horizontally and serving as a fulcrum for the agitator lever 20. Said ring 23 has threaded perforations 10 to receive said screws which are driven inward sufficiently to set tightly against the arm 3 to secure said ring. The lever 20 has apertures 25' and 26' in its looped part 20' for said screws 25 and 26 respectively, 15 which apertures are large enough to provide a loose fit for the screws and so permit limited movement of said agitator in all directions. The loop 20', which encircles the arm 3 and ring 23, is secured by means 20 of a machine screw 28, and the agitator wire 18 is preferably clamped by said screw rigidly to the agitator. By this means the agitator wire may have limited universal movement and may be moved for instance 25 longitudinally in the jet aperture and also swung crosswise and vibrated in various directions whereby all the soot and other material clogging the jet aperture may be effectively loosened and removed at the will 30 of the operator. Being held permanently in the aperture 4, the cleaner 18 is always effective and is never out of order.

The guide member 30, which is disposed in spaced relation over the jet orifice 4 and 35 which also contains the mixing chamber 31, is suspended by a pair of bolts 33 provided with nuts 34 bearing on the upper side of plate 9, or the plate apertures 35 for said screws may be threaded, as will be understood, for engaging said screws. Said guide member 30 has a shape resembling the inverted frustum of a hollow cone, and is provided with a pair of outstanding lugs 37 at opposite sides at or adjacent to the upper 40 edge, said lugs being perforated to receive said supporting bolts 33.

A baffle plate or button 40 is disposed horizontally in the mixing chamber 31 in coaxial relation thereto, whereby the upper 45 wardly passing vapor and flame are spread out divergently. Said plate or button 40 is carried by a transverse rod 42 the ends of which are fixed rigidly on said guide adjacent to its upper edge as at 43. Said button 40 is preferably in the form of a bolt provided with a broad flat head constituting the button proper, the shank being disposed upward and provided with a nut 45 arranged to set tightly against the supporting rod which passes horizontally through the shank of the bolt adjacent to the head, said shank being perforated at 46 to receive said rod. The supporting screws 33 are tightened sufficiently to cause the upper end 60 of the baffle bolt, or nut 45 carried thereby,

to bear against the under side of the upper arm 2 and so hold the guide and its associated parts rigidly in place.

The front end of the upper or intake arm 2 is provided with a detachable fitting 48 adapted to provide for ready access to the interior of the upper arm. For this purpose there is provided a valve fitting of tubular character, one end of which as at 50 is conical in shape and fits tightly and 70 wedgingly in the end of the upper arm. The conical end is also provided with an outwardly facing annular shoulder 53 to receive the pressure of the connector 55 which is interiorly threaded at one end to engage 75 the exterior threads on the outer end of the upper arm, the opposite end being interiorly shouldered at 56 to engage the shoulder 53 of said fitting. The source of fuel is connected to said fitting by means of a small 80 tube 57 of flexible character which may be made of metal such as copper, brass or the like. A small hand wheel 58 is arranged to open and close the valve in said fitting whereby the fuel supply is controlled. 85 When the connector is unscrewed from arm 2, said fitting may be removed and moved back a considerable distance by virtue of the flexible nature of the supply tube, whereupon the wick member may be removed 90 and inverted or cleaned or a new one substituted.

In order that a thoroughly tight closure may be effected by the cap 3' without the use of any sealing compound, and in order 100 that such a closure may be removed and replaced readily, a conical plug 60 is provided and adapted to fit in the end of the tube and is also adapted to be forced tightly into place by the cap 3', said plug and tube 105 being ground to fit.

The method of using and operating the burner described is as follows:—Whenever the burner fails to burn vigorously the operator grasps the handle 21' of the 110 agitator control rod 21 and moves same inward and outward as well as laterally in all directions and thereby thoroughly cleans the jet aperture 4. This may be done equally well when the burner is in use as when the 115 fuel is turned off. Although the wire 18 is always in operative position in the aperture 4, it does not interfere with the vapor and flame and never puts out the fire.

Whenever it is thought that the wick 120 needs attention the fuel is cut off by the valve 58 and the fitting 48 is removed. The hand tool 15 is then inserted at the open end of arm 2 and engaged with the loop 16 and the wick removed. In replacing the wick it 125 is preferable to reverse it as the inner half receives the most heat, being directly in line with the burner jet and flame, and by reversing the wick both ends are treated alike. Any deposit of carbon on the wick 130

may be burned off by passing the wick through a flame while removed from the pipe 2.

The button or baffle 40 confines the flame 5 so that it does not go out as sometimes occurs when said baffle is omitted. The hollow cone or guide 30 serves effectively to reduce and minimize the noise of the flame and renders it more uniform and constant 10 and free from liability to go out.

Although but one specific embodiment of this invention has been herein shown and described, it will be understood that numerous details of the construction shown may be 15 altered or omitted without departing from the spirit of this invention as defined by the following claims.

I claim:

1. A hydrocarbon burner having a horizontal tubular arm, and beneath said arm a torch cup provided with an upstanding stud secured to the under side of said arm, the connection for said stud and arm including a sleeve fitting loosely upon said arm and 25 having a threaded aperture on its lower side, said stud also being threaded whereby the upper end of the stud may be set tightly in said aperture and against said arm, and said arm having a jet aperture.

2. A hydrocarbon burner having a horizontal tubular arm, and beneath said arm a torch cup provided with an upstanding stud secured to the under side of said arm, the connection for said stud and arm including 35 a sleeve fitting loosely upon said arm and having a threaded aperture on its lower side, said stud also being threaded whereby the upper end of the stud may be set tightly in said aperture and against said arm, said 40 arm having a jet aperture, a second sleeve mounted loosely outside the first mentioned sleeve, the outer sleeve being provided with a large aperture adapted to receive said stud loosely, a jet cleaner secured to the outer sleeve, and means for rocking the outer sleeve manually for cleaning the jet aperture.

3. A hydrocarbon burner including means for vaporizing the fuel and discharging it upward in jet form, a guide and mixing

member of inverted hollow simple conical 50 frustum shape disposed entirely above the fuel jet in spaced relation thereto and in line therewith, and a laterally extending jet cleaner disposed between said jet and said member.

4. A hydrocarbon burner, comprising a U-shaped tube disposed horizontally one arm over the other, the lower arm having a fuel jet aperture facing upward, a flame distributing plate carried horizontally over said 60 aperture by and on the upper side of the upper arm, and a guide member supported between said arms and coaxial with said aperture and plate, said guide member having a fuel and air mixing chamber containing a 65 baffle plate or button disposed centrally therein.

5. A hydrocarbon burner, including a guide member of inverted hollow conical frustum shape open at the lower end to receive fuel vapor together with air, and a baffle plate or button centrally disposed entirely in the open upper part of said guide member.

6. A hydrocarbon burner having a jet 75 aperture for the discharge of vaporized fuel to be burned, a metallic cleaner including a filiform member permanently fitting loosely in said aperture, a loosely pivoted support for said member, and manual means arranged 80 and adapted to agitate said support member for removing carbon or other obstructing material from said aperture.

7. A hydrocarbon burner having a jet 85 aperture for the discharge of vaporized fuel to be burned, a metallic cleaner including a filiform member permanently fitting loosely in said aperture, a loosely pivoted support for said member, and manual means arranged and adapted to agitate said support 90 member for removing carbon or other obstructing material from said aperture, said support being in the form of a short sleeve fitting loosely on the pivot and burner.

Signed at Chicago this 27th day of 95 August, 1918.

JEFFERSON CLARK GIBSON.
